HANGER FOR DEAD ANIMALS

Larry L. Hulsey, Rte. 2, Box 1460,
Madras, Oreg. 97741

Filed Oct. 7, 1968, Ser. No. 13,872

Term of patent 14 years

Int. Cl. D15—99

U.S. Cl. D11—1

FIGURE 1 is a side elevational view of a hanger for dead animals showing my new design;

FIGURE 2 is a top plan view of the hanger; and

FIGURE 3 is an end view of the hanger taken from the left of FIGURE 1.

I claim:

The ornamental design for a hanger for dead animals, as shown.
